UNITED STATES PATENT OFFICE.

EDWIN G. VAN WIE, OF DETROIT, MICHIGAN, ASSIGNOR TO DETROIT STOVE WORKS, OF DETROIT, MICHIGAN, A CORPORATION OF MICHIGAN.

DESIGN FOR A STOVE.

47,084.

Specification for Design.

Patented Mar. 9, 1915.

Application filed December 20, 1913. Serial No. 808,044. Term of patent 14 years.

To all whom it may concern:

Be it known that I, EDWIN G. VAN WIE, a citizen of the United States of America, residing at Detroit, in the county of Wayne and State of Michigan, have invented a certain new, original, and ornamental Design for Stoves, of which the following is a specification, reference being had therein to the accompanying drawings, forming part thereof, in which the figure is a perspective view of a stove, showing my new design.

The design consists of a gas range having an open top and having the appearance below the open top substantially as shown in the drawing.

I claim:

The ornamental design for a stove, substantially as shown and described.

EDWIN G. VAN WIE.
